UNITED STATES PATENT OFFICE.

AETHUR P. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR LOOMS.

Application filed July 2, 1926. Serial No. 120,195.

This invention relates to improvements in weft detectors for looms and it is the principal object of the invention to provide a detector very light in its action and exerting very little pressure on the yarn.

With the introduction of fine yarns, such as rayon, it has been necessary to develop weft detectors which exert very little pressure because of the fact that a bobbin of fine yarn will remain active for such a length of time that the ordinary weft detector will fray or abrade the yarn before the latter has been woven off the bobbin and it is accordingly an important object of my invention to provide a weft detector formed preferably of light wire yarn engaging portions which are held in position by a small spring.

Weft detectors of the type shown in patent 20 to Ryon No. 972,722 have gone into very extensive use and have been found very satisfactory, said detectors being of the so-called double contact type and having a yarn penetrating wedge-shaped detector 25 which cooperates with an angularly moving notched or toothed yarn impinging member. Such detectors are commonly made with at least two springs and it is a further object of my invention to employ the same principle as that employed in the Ryon detector 30 with the use of a single spring.

When detectors are placed on the magazine end of automatic box looms it is necessary to withdraw the same on transferring 35 beats and it is accordingly a further object of my invention to provide for withdrawing both of the yarn engaging detecting members on transferring beats by acting on one of said detectors, there being an interengaging 40 connection between both detectors so that they will be withdrawn together without giving an indication.

In automatic box looms the control for the magazine is usually very close to the detector, making it possible to have a short connection between the weft detector and the magazine and it is accordingly a further object of my invention to provide a very simple and light device for communicating 45 indication of weft exhaustion from the detector to the controller which is controlled by the laterally movable detector and positioned by the same spring which controls the detectors.

With these and other objects in view 55 which will appear as the description proceeds, my invention resides in the combination and arrangement of parts hereinafter described and set forth in the claims.

In the accompanying drawings wherein I 60 have shown a convenient embodiment of my invention,

Fig. 1 is a top plan view of my detector showing associated parts of the replenishing mechanism, parts of which are in section, 65

Fig. 2 is a front elevation of the detector taken in the direction of arrow 2, Fig. 1, parts being broken away,

Fig. 3 is a view similar to a portion of Fig. 1 with the cap of the detector removed 70 showing the parts in the position they assume on the forward stroke of the lay when in contact with a sufficient supply of weft, and

Figs. 4 and 5 are vertical sections on lines 75 4-4 and 5-5, respectively, of Fig. 3.

Referring to the drawings it will be seen that I have provided a loom frame 10 to which is bolted the foot 11 of a weft replenishing mechanism 12 provided with a 80 hub 13 through which extends stud 14 secured thereto by a set screw 15. Pivotaly mounted on the stud is a transerrer arm 16 having depending feet 17 between which extends a pin 18 for the transerrer latch (not 85 shown).

A bracket 19 is bolted to the loom frame and has slidably mounted therein for vertical movement a block 20 on which is pivoted a floating actuator lever 21 the inner 90 end of which is pivotally connected to an upwardly extending rod 22 which is connected to the weft replenishing mechanism (not shown). The outer end of the lever 21 extends through an upstanding horn 23 95 formed preferably as part of the bracket 19 and having a slot 24 therein which guides the outer end of the actuator lever. On each detecting beat of the loom when the shuttle is on the magazine side of the loom the 100 block 20 will be given a downward movement and if sufficient yarn is present the outer end will move downwardly freely in slot 24 leaving the connector 22 unmoved, but if insufficient yarn is present the outer 105 end of the actuator lever will be interrupted in its descent to cause a downward movement of the connector 22, the effect of which

will be to indicate for a change of operation in the loom. The matter thus far described is of common construction and may be as set forth in the aforesaid patent and also in 5 Patent No. 1,030,748.

In carrying out my improvements I extend the bracket 19 to the right as shown in Fig. 1 and secure thereto a bed 30 having a cap 31. Said bed is hollow and has lateral 10 walls 32 the left hand one of which is provided with a lug 33. Said bed is further provided with guiding and bearing surfaces 34 and the rear portion of the bed is further provided with a pin 35.

15 The laterally moving yarn impinging detector is formed preferably of a single piece of wire 36 having the rear surface thereof notched and bent to extend parallel to the bobbin as at 37, the forward end of the wire 20 36 being bent as at 38 to rest on one of the guides 34 and then extending across the bed to rest on the other guide as at 39. Said portion 39 normally cooperates with the lug 33 which serves as a pivot about which the 25 detector may move. Said wire 36 is provided with a crimp 40 to receive the forward end of a very light tension spring 41 the rear end of which is secured to the lug or projection 35. A boss 42 preferably cast integral 30 with the bed engages the forward part of the wire 36 as indicated in Fig. 1, said lug and boss 33 cooperating with the spring 41 to position the yarn engaging rear end 37.

35 The yarn penetrating detector is indicated at 43 and has a rear pointed end 44 which extends slightly behind the teeth of the detector 36, the forward portion of the detector 43 bridging the wire 36 as at 45 and extending to the right to be supported on 40 the right hand guide 34. A second boss 46 cast on the bed guides the detector 43 to prevent movement thereof to the left, lug 42 acting to prevent movement to the right. A rib 47 on the cap 31 engages the top of the 45 bent part of wire 43 to prevent upward movement thereof. The wire 36 is extended forwardly of the bend 39 and downwardly as at 48 as shown in Figs. 3 and 5, and to the right of the left guide 34. A withdrawing 50 link 49 passes behind the end 48 of detector 36 and has portions resting on the guides 34. Said link 49 is guided in the front wall of the bed 30 and is offset to lie in front of pin 18. Said end 48 lies between 55 the pivot lug 33 and the spring 41 so that when being withdrawn the detector 36 will not move angularly but will move forwardly with a right line or parallel motion.

60 The controller for the actuator lever 19 is preferably formed of a single piece of bent wire indicated at 50 and has a rearwardly extending portion bent down and under the detector 36 and up on the opposite side thereof as indicated in Fig. 4 at 51. The intermediate portion of the controller is coiled

as at 52 and extends around a pivot forming screw 53 secured in the cap 31 and the forward portion of said controller is extended to the left as indicated in Fig. 1 and is bent rearwardly as at 54 to be guided on a shelf 70 55 of the horn 23.

Under normal conditions the spring 41 will hold the angularly moving detector 36 in the position indicated in Fig. 1 in full lines and inasmuch as the detector 43 bridges a portion of the angularly moving detector the former will also be properly positioned with respect to the bobbin, this result being accomplished by the single spring 41. So long as there is sufficient yarn present for continued weaving the wedge-shaped member 44 will enter the yarn a sufficient distance to permit the teeth on the detector 36 also to enter the yarn to restrain lateral movement thereof, and as the lay continues to move forwardly the bobbin B will move the detector from the position shown in Fig. 1 to that shown in Fig. 3, the curved part 39 moving away from the lug or boss 33 and the end 54 of the controller remaining out 80 of the path of the actuator lever 21.

When insufficient yarn for continued weaving is present, however, the wedge 44 will not penetrate the yarn a sufficient distance to permit contact of the latter with the teeth of detector 36 and as the detector 43 is moved forwardly by the continued advancing movement of the detector the bridged portion 45 will move the adjacent part of the detector 36 forwardly. Inasmuch as spring 41 lies between the bridge and the lug 46 the latter will become a pivot point about which the detector 36 will be moved to some such a position as indicated in dotted lines in Fig. 1. This angular 100 movement on the part of the detector 36 causes a corresponding right hand oscillation of the controller 50, causing the end 54 of the latter to pass under the outer end of the actuator lever 21 as indicated in dotted lines in Fig. 1. Downward movement of the actuator will therefore be resisted and indication of weft exhaustion will be communicated to the magazine as described hereinbefore.

110 On the subsequent transfer the stud 18 will be moved forwardly to engage the link 49 and both detectors will be moved out of the path of the incoming bobbin, this movement on the part of the wedged detector being accomplished without angular movement 120 on the part of the angularly movable member 36 because of the fact that the end 48 lies between the pivot lug 33 and the spring 41.

125 From the foregoing it will be seen that I have provided a very light weft detector having yarn penetrating and yarn impinging elements both of which are held in normal yarn engaging position by a single 130

spring which may be made very light to cause practically no wearing or abrasion of the yarn. Furthermore, it will be seen that the withdrawing link 49 is effective to withdraw both detectors and that said link is connected to the angularly movable detector 36 at such a point as will prevent indicating movement of the latter on the withdrawing movement. It will also be noted that the controller for the actuator lever is very light and is positioned by the spring 41 through the U-shaped connector 51.

Having thus described my invention it will be apparent that changes and modifications may be made therein by those skilled in the art without departing from the spirit and scope of the invention, and I do not wish to be limited to the details herein disclosed, but what I claim is:

1. In a weft detector for looms, a stationary support, an angularly movable yarn impinging detector slidably mounted on the support and having a right line sliding motion with respect to the support when in contact with sufficient weft and having an angular motion with respect to the support when presented to an insufficient supply of weft, resilient means holding the detector in normal position, and a second detector having a yarn penetrating part extending beyond the yarn impinging detector to enter a sufficient supply of weft, said detectors being connected together, said second detector when in engagement with insufficient yarn moving the first detector before the same engages the yarn to move said first detector angularly and the resilient means acting to give the impinging the detector an angular motion.

2. In a weft detector for looms, a stationary support, an angularly movable yarn impinging detector slidably mounted on the support and having a right line sliding motion with respect to the support when in contact with sufficient weft and having an angular motion with respect to the support when presented to an insufficient supply of weft, resilient means holding the detector in normal position, a second detector having a yarn penetrating part extending beyond the yarn engaging surface of the impinging detector, and a connection between the detectors lying between the yarn impinging detector and the resilient means to cause angular movement of the impinging member by the action of the resilient means when the penetrating detector engages a bobbin supplied with insufficient weft.

3. In a weft detector for looms, a stationary support, a yarn impinging detector slidably mounted on the support, means defining a pivotal connection between the detector and the support, said detector sliding forwardly in the support without angular motion when in contact with sufficient weft, a second detector having a yarn penetrating

part extending beyond the yarn engaging surface of the impinging detector, means defining an operative connection between the detectors, and resilient means connected to the impinging detector at a point between the pivot of the same and the operative connection between the detectors, said penetrating detector when in contact with a bobbin with insufficient weft moving the impinging detector forwardly before the same can engage the yarn on the bobbin, the resilient means under these conditions causing angular movement of the impinging detector.

4. In a weft detector for looms, a stationary support, a yarn impinging detector slidably mounted on the support, means defining a pivotal connection between the detector and the support, said detector sliding forwardly in the support without angular motion when in contact with sufficient weft, a second detector having a yarn penetrating part extending beyond the yarn engaging surface of the impinging detector, means defining an operative connection between the detectors, resilient means connected to the impinging detector at a point between the pivot of the same and the operative connection between the detectors, said penetrating detector when in contact with a bobbin with insufficient weft moving the impinging detector forwardly before the same can engage the yarn on the bobbin, the resilient means under these conditions causing angular movement of the impinging detector, an actuator to effect a change in the operation of the loom, and a controller pivoted on the support and having a part operatively connected to the angularly movable detector and having another part to cooperate with the actuator at the time of angular motion of the yarn impinging detector.

5. In a weft detector for looms, a stationary support, a yarn impinging detector slidably mounted on the support, means defining a pivotal connection between the detector and the support, said detector sliding forwardly in the support without angular motion when in contact with sufficient weft, a second detector having a yarn penetrating part extending beyond the yarn engaging surface of the impinging detector, means defining an operative connection between the detectors, resilient means connected to the impinging detector at a point between the pivot of the same and the operative connection between the detectors, said penetrating detector when in contact with a bobbin with insufficient weft moving the impinging detector forwardly before the same can engage the yarn on the bobbin, the resilient means under these conditions causing angular movement of the impinging detector, an actuator to effect a change in the operation of the loom, and a controller pivoted on the support and having a part operatively connected to the angularly movable detector and having another part to cooperate with the actuator at the time of angular motion of the yarn impinging detector.

ected to the angularly movable detector and having another part to cooperate with the actuator at the time of angular motion of the yarn impinging detector, said controller being in contact with opposite sides of the angularly movable detector to be moved positively by the latter, the resilient means serving thereby to place the controller as well as the detectors in normal position.

10. 6. In a weft detector for looms, a stationary support, an angularly movable yarn impinging detector slidably mounted on the support and having a right line sliding motion with respect to the support when in contact with sufficient weft and having an angular motion with respect to the support when presented to an insufficient supply of weft, resilient means holding the detector in normal position, a second detector having a

yarn penetrating part extending beyond the 20 yarn engaging surface of the impinging detector, a connection between the detectors lying between the yarn impinging detector and the resilient means to cause angular movement of the impinging member by the 25 action of the resilient means when the penetrating detector engages a bobbin supplied with insufficient weft, and means operatively connected to one of the detectors to withdraw the same from the path of the incoming bobbin at the time of transfer, the connection between the two detectors being depended upon to move both detectors when one of the same is moved.

In testimony whereof I have hereunto af- 30 fixed my signature.

ARTHUR P. PAINE.
